(57) **CLAIM**

The ornamental design for a 3D printed mold inserts, as shown and described.

DESCRIPTION

FIG. 1 is a perspective view showing the design;
 FIG. 2 is a side view of the design shown in FIG. 1;
 FIG. 3 is a top elevational view of the design shown in FIG. 1;

FIG. 4 is a bottom elevational view of the design shown in FIG. 1; and,
 FIG. 5 is a cross-sectional view taken along Line 5 of FIG. 1.

The broken line portions in the drawings are for illustrative purposes and do not form part of the claimed design.
